TELEMETERING DEVICE

Carlton W. Bristol, Naugatuck, Conn., assignor
to The Bristol Company, Waterbury, Conn., a
corporation of Connecticut

Application September 14, 1934, Serial No. 743,967

6 Claims. (Cl. 177—351)

The invention relates to telemetering systems; and more particularly to receiving devices for use therein and adapted, for example, to a system of the nature set forth in U. S. Patent #1,822,683 (reissued January 2, 1934, as #19,039). In systems of this type, signals of a time duration corresponding to a quantity of variable magnitude—and controlled jointly by a substantially constant speed motor means constantly operable and a quantity responsive means—are transmitted, as recurrent electrical impulses of equal magnitudes but varying durations, over a suitable connecting circuit to a receiver device comprising substantially constant speed motor means and means actuated thereby for the duration of said signals.

The present invention has for an object the provision of a receiving device, for use in a telemetering system of the aforesaid type, which shall be free from the objectionable feature of mechanical backlash which has heretofore characterized receiving mechanisms utilized in such systems.

A further object of the invention resides in the provision of receiving apparatus embodying simple solenoidal magnets of standard construction whereby there is eliminated the use of intricately designed electromagnetic structures which require provision for both axial and rotary movement.

Another object of the invention resides in the provision of a receiving device in which the parts subject to intermittent motion shall be of relatively small mass to reduce inertia effects to a minimum.

A further object of the invention resides in the provision of means whereby there is given a positive indication of the presence of trouble in the transmission means between the receiving and transmitting instruments or of trouble at the latter instrument, whereby the system may become inoperative or its indications devoid of significance.

A still further object of the invention contemplates a compact, inexpensive and rugged receiving device capable of ready production in large quantities.

In carrying out the invention, a receiving indicating and/or recording and/or controlling instrument is afforded, the same comprising an epicyclic train having gear members and a planetary member which are associated with a braking element responsive to impulses transmitted thereto over a two-conductor circuit from a transmitting device comprising quantity responsive

means, motor means continuously operable at substantially constant speed, and means controlled jointly by the responsive and motor means to produce the signals of a time duration corresponding to the quantity affecting the quantity-responsive means. One of the said gear members, furthermore, is adapted to operate continuously and another to be stopped by said braking element in accordance with the transmitted impulses, whereby the position of said planetary member and associated mechanism may be governed.

The nature of the invention, however, will best be understood when described in connection with the accompanying drawings, in which:

Fig. 1 is a fragmentary front elevation of the novel receiving device, with portions broken away.

Fig. 2 is a plan view thereof.

Fig. 3 is a longitudinal section through the device taken on the line 3—3, Fig. 2 of the drawings, and looking in the direction of the arrows.

Fig. 4 is a front elevation of a modified form of a portion of the receiving device; and Fig. 5 is a perspective view illustrating a further modification in the same.

Figs. 6 and 7 are respectively a front elevation, with parts broken away, and a side elevation, of a transmitting device suitable for use with the novel receiving device.

Fig. 8 illustrates, more or less diagrammatically, the arrangement of the various members in a telemetering system.

Referring to the drawings, more particularly Figs. 1 to 3 thereof, 10 and 11 designate suitable frame plates for the mounting of the various parts of the novel receiving device, the former plate constituting the base and the latter the front plate. A dial plate 12 is also provided, being located in front of the plate 11; and the said plates are secured together and spaced apart by suitable posts 13 and a post 14, the former being disposed near the extremities of said plates and the latter centrally located and provided with a cylindrical portion adapted to serve as a bearing.

Between the plates 10 and 11 are mounted for rotation two similar epicyclic trains or differential gearings 15 and 16 carried on spindles 17 and 18, respectively, and having the following operative relationship. The train 15 comprises two bevel gears 20 and 21 both running freely on the spindle 17, and both having meshing engagement with one or more beveled pinions 22 carried on a shaft member 23 located perpendicularly to the spindle 17, the shaft being mounted rotatably thereon through a hub 24. Thus, if the spin-

idle 17 be held stationary and either of the gears 20 or 21 rotated, the other of the gears will tend to rotate in the opposite direction with the same angular velocity. Moreover, if either of the gears 5 20 or 21 be held stationary and the other gear rotated, the pinions 22 will roll upon the stationary gear as planet wheels and will impart to the shaft 23 an angular velocity which is half of that with which the gear is rotated.

10 Attached to beveled gear 20 is a spur gear 25 and to the gear 21 a braking wheel 26 adapted for positive engagement with an oscillatable brake element 27, either by friction or by a more positive means and whereby the said braking wheel 15 26 and gear 21 may be brought to a positive standstill.

15 The train 16 is a duplicate in all respects to the train 15, having the two beveled gears 28 and 29 running freely upon the spindle 18; and having 20 also in common mesh one or more beveled pinions 30, carried upon a shaft 31 attached by a hub 32 to the spindle 18 for rotation thereon. Thus, under conditions as hereinbefore set forth, the 25 said pinions 30 may be caused to function as planet wheels.

30 There is attached, also, to the beveled gear 28 a spur gear 33 which meshes with the similar spur gear 25 of the other train. As in the case of said other train, a brake wheel 34 is carried by 35 the opposite gear 29 of train 16; and this wheel is adapted to be engaged by the brake element 27 alternatively to the brake wheel 26.

35 A constant speed motor 35 is carried by the base plate 10 and may be of the well known A. C. synchronous clock type. Through a pinion 36 meshing with the gear 33, and driven by the said motor, continuous rotation in opposite directions is communicated to the said gears 25 and 33, and 40 through these to the respective associated trains 15 and 16.

45 The shaft 23 of train 15 is extended at one end beyond the periphery of the beveled gears 20 and 21, forming a stop 37 adapted to engage an adjustable screw member 38 threaded through one of the posts 13 and locked thereto by a thumb nut 39. A spiral spring 40, having its inner end affixed to the spindle 17 and its outer end to a post 41 on the rear surface of plate 11, serves to urge the spindle in a counter-clockwise sense 50 and to hold the stop 37 in engagement with the end of screw 38. Spindle 17 is extended through the plate 11 and carries a crank member or dog 42 whose position at all times will correspond to that of said shaft 23.

55 Similarly, the shaft 31 of the gear train 16 is extended to form a stop 43 adapted to engage a screw member 44 threaded through and adjustably locked to another of the posts 13 by a nut 45. The spiral spring 46 between the spindle 18 and an abutment or post 47 on the plate 11, serves to urge the said spindle 18 in a clockwise sense and to hold stop 43 in engagement with the end of a screw 44. A crank or dog 48 is fixed to an extension of the spindle 18 so that its position at all times will correspond to that of the shaft member 31.

60 A lever arm 50, journalled upon a cylindrical portion of post 14, carries the brake element 27 as well as an armature 51 of ferromagnetic material within the field of an electromagnet 52, which tends to actuate the lever arm in opposition to a spring 53 attached thereto, so that under influence of the magnet the brake will be applied to the wheel 34, and under that of the 65 spring it will be applied to the wheel 26.

Carried on spindles extending rearwardly of the dial plate 12 and in alignment with the spindles 17 and 18, respectively, are pinions 54 and 55, having attached thereto projecting arms 56 and 57 adapted to be engaged by the dogs 42 and 48, respectively, so that rotation may thereby be imparted to the said pinions. Centrally disposed at the rear of the dial plate 12, and fixed to a spindle 58 which extends through to the front of the dial plate 12, is a gear member 59 meshing 10 with both the pinions 54 and 55. Carried by the forward extension of the spindle 58 is a pointer 60, which, by its position relatively to a graduated scale 61 on the dial plate 12, serves to provide an indication of the angular position of the gear 15 member 59.

The operation of the apparatus as thus far described is as follows: The motor 35 is caused to operate continuously so as to impart to the gear 33 rotation in a counter-clockwise sense 20 and to the gear 25 rotation in a clockwise sense. Assuming for the moment that the brake element 27 be inoperative, it will be seen that, the shaft members 23 and 31 being restrained against their stops by the springs 40 and 46, the pinions 22 and 25 30 will rotate about their respective axes; and the brake wheels will revolve freely, wheel 26 in a counter-clockwise sense and wheel 34 in a clockwise sense. Under actual conditions, however, wheels 26 and 34 will never both be simultaneously free, one or other being engaged by the braking element 27, according to whether or not the magnet 52 is energized.

Assuming that the magnet is energized, the braking element 27, under influence of the magnet, will engage the brake wheel 34, definitely stopping its rotation. Under this condition the bevel gear 29 will remain at rest, and upon its surface, actuated by the bevel gear 28, will roll the pinions 30, causing the shaft 31 and the parts 40 carried thereby to rotate in a counter-clockwise sense with an angular velocity half that of the gears 28 and 33, winding up the spring 46. This will cause the dog 48 to approach the arm 57, and, after engaging the same, will cause the pinion 55 45 to rotate, driving the gear member 59, whereby the pointer 60 will tend to advance across the scale 61 in a clockwise sense.

Assuming, now, that the magnet 52 be de-energized, the armature 51 will at once be released, 50 allowing the brake member 27 under the influence of spring 53 to disengage the wheel 34 and immediately to engage the braking surface of the wheel 26. The brake wheel 34 being no longer restrained by the brake member 27, the shaft 31 55 with the parts carried thereby, under the influence of the spring 46, will have been returned to the position where the stop 43 engages the screw 44, the dog 48 leaving the arm 57 in its position of maximum excursion.

60 The pinions 54 and 55 both being in permanent mesh with the gear 59, the arms 56 and 57 will at all times bear a definite position relationship to each other and to the pointer 60. Thus, the position in which the arm 56 will lie at the instant the dog 42 begins its excursion will depend upon the position in which the arm 57 was left by the dog 48 at the time the brake-wheel 34 was released. The relative position of the elements of the mechanism as shown in Figs. 1, 2 and 3 65 70 is that in which the dog 48 is about to engage the arm 57.

Upon the braking element 27 engaging the brake wheel 26, the differential train 15 will be caused to function in a manner identical with 75

that described for the train 16, so that the dog 42 will advance in a clockwise sense approaching the arm 56 which lies as it was left at the instant of disengagement between the dog 48 and the arm 57. If the engagement of the braking element 27 with the wheel 26 is of sufficient duration, the dog 42 will reach the arm 56 and will cause it to rotate the pinion 54, whereby the pointer 60 will be caused to travel across the scale 61 in a counter-clockwise sense.

At the same time, through the action of pinion 55, the arm 57 will be forced toward the dog 48 as it lies in the position to which it was reset when the brake-wheel 34 was released. Thus it will be seen that the pointer 60 will tend to lie in a position relative to the scale where it was left by the latest of the impulses coming alternately from the trains 15 and 16, and that if the excursion of either of these exceeds the magnitude of its previous excursion the pointer will be advanced to a new position on the scale.

It will thus be apparent that if the magnet 52 be energized for a time interval sufficiently long for the pointer 60 to make a complete transit of the scale 61, then momentarily de-energized, and then re-energized for a similar interval, the pointer will take up a position at the upper limit of the scale. Similarly, if the magnet be left de-energized for a time corresponding to the complete transit of the pointer and then momentarily energized, the pointer will take up a position at the lower limit of the scale.

It will further be apparent that if there be established a recurrent series of electrical impulses, in which equal cycles are made to correspond in duration with the time of transit of the pointer, the latter, under the alternating influence of the trains 15 and 16, will tend to take up on the scale a position in which its excursion from the lower limit of the scale (i. e. its total deflection) will bear to the total length of the scale a ratio equal to that existing between the length of the interval in each cycle during which the magnet 52 is energized and the time of the complete cycle.

It will be observed that as no definite stops are provided for the arms 56 and 57, the position of the pointer will at any time be determined by the latest of the impulses from one or other of the dogs 42 and 48, and that the normal working angle of deflection of the pointer will be governed by the angle through which either of these dogs will rotate during the normal time interval of a cycle.

If the parts be so proportioned and adjusted that the normal angle or travel of the pointer corresponds exactly to the normal time interval as hereinabove set forth, and the pointer be free to overtravel the scale if so impelled, it will be apparent that, so long as the transmitting apparatus and circuit function in a normal manner, the pointer will remain within the limits of the scale, and that an excursion of the pointer above or below these limits will represent a period of energization or de-energization prolonged beyond the normal time interval of the transmitter, which in turn will provide an indication of faulty circuit conditions in the connecting line or of malfunctioning of the transmitting device.

While the epicyclic trains embodied in the mechanism as above set forth take the form of bevel gear differentials, it will be apparent to those skilled in such mechanisms that identical performance could be obtained by embodying in

the design trains taking other mechanical forms.

For example, an epicyclic reverted gear such as that shown in Fig. 4 (sometimes known as a "Crypto gear") could be substituted for the type used in the trains 15 and 16 of Figs. 1, 2 and 3, with equivalent results. Here spur gear 65 carried upon a shaft 66 is to be directly connected to the elements of the mechanical system driven from the motor. An annular gear 67 running freely upon the shaft 66 has its outer surface adapted to serve as a brake wheel. In the space between the outer periphery of the gear 65 and the inner surface of the gear 67 runs a planetary gear 68, carried upon an arm 69, which is free to swing about the shaft 66 as a center of rotation. The arm 69 corresponds to the dog 42 indicated in Figs. 2 and 3.

The general modification of the associated mechanism necessary to incorporate this gear train in the place of those shown whereby equivalent results will be obtained will be apparent to those versed in the art, and requires no further elucidation here. It will also be apparent that the functions of the gears 65 and 67 can be interchanged, so that 67 may be the driven gear and 65 attached to the brake-wheel.

A further alternative, whose application will also be apparent to those skilled in the art, is shown in Fig. 5. Two similar spur gears 70 and 71 are mounted coaxially on a common shaft 72, one at least being free to rotate thereon. Two spur pinions 73 and 74 are supported on an arm 75, also rotatable about the shaft 72. The pinion 73 meshes with the gear 70 and the pinion 74 with the gear 71, and the pinions mesh with each other. Thus it will be seen that there has been provided a differential gearing whose performance will in every respect be a duplicate of the train 15 or 16 in Fig. 1.

It will further be apparent that in any of the several types of epicyclic train which have been described, the driving forces as they affect the meshing of the gears will never be subject to reversal, so that under all operating conditions backlash between the gears will be taken up, whereby errors due to lost motion will be eliminated from the mechanism.

So far as the transmitting device for operation of the receiving means aforesaid is concerned, any suitable device may be utilized which will provide for recurrent cycles of impulses of current whose duration is representative of the position of a deflecting element as actuated by the quantity measured thereby. For example, and referring now to Figs. 6 and 7, a transmitting device is shown and in which 81 indicates a supporting base formed into a U-shape, carrying upon its rearward portion a measuring element, such as a Bourdon spring 82, and having its bent-up portions perforated to form guides for a bar 83 free to slide vertically therein. The Bourdon spring 82 is fixed at one end to the supporting member 81 and has attached to its free end a shaft 84 which passes centrally through the spring and projects to the forward part of the supporting member 81 and bears upon its forward end an indicating pointer 85.

Fluid pressure which it may be desired to measure, is conveyed to the interior of the Bourdon spring by a pipe 86, whereby the angular position of the free end of the spring and shaft 84 and the pointer 85 may be made representative of, and substantially proportional to, the pressure under measurement. By means well known to those skilled in the art of measurement, the

pressure in the pipe 88 may be made representative of any one of a variety of magnitudes, such as temperature, head of water, etc.

Attached to the forward part of the supporting member 81 is a dial plate 87, having engraved thereon a graduated scale to which is juxtaposed the indicating extremity of the pointer 85, so that the position of the pointer as indicated on the scale 87 becomes a measure of the pressure 10 within the Bourdon spring 82 or of the magnitude represented thereby. Carried upon the shaft 84 immediately behind the bar 83 is a metal sector 88 having a contour conformed to a polar curve about the center line of the shaft 84, whereby the 15 radius of the sector in a selected fixed direction will vary in accordance with the angular position of the sector. Thus if the contour of the sector be made to take the form of an Archimedean spiral the radius in a chosen fixed direction 20 will be substantially proportional to the pressure in the Bourdon tube, as indicated by the pointer 85 on the scale 87.

Rotatably mounted upon a hub 89, concentric with the shaft 84 is a gear member 90 carrying 25 a cam member 91, on the upper surface of which rests a small roller 92 pivoted on a stud or bracket 93 which is fixed to the sliding bar 83, whereby as the cam member 91 is caused to rotate, the bar 83 will be smoothly reciprocated up and down. 30 The stud 93 passes over the sector 88 at a point vertically above the center line of the shaft 84, and bears an insulated contact piece 94 adapted to engage the contour of the sector and thus to form an electrical contact with the body of the 35 instrument. Carried on the support of the instrument are two terminals 95 and 96, one electrically connected to the frame and the other connected through a flexible lead to the contact piece 94.

40 A constant speed motor 97, which may be of the A. C. synchronous clock motor type, is mounted upon the frame of the instrument; and through a pinion 98, meshing with the gear 90, the motor serves to rotate the cam member 91 at a constant velocity. Thus, as the motor is caused to operate, the bar 83 will move up and down periodically, and as the contact piece 94 engages the sector 88, the weight of the bar will be taken thereby, and the cam will continue to 50 rotate freely until it re-engages the roller 92 and lifts the bar.

If the contour of the cam member 91 has an Archimedean spiral conformation both on its rising and falling portions, the velocity of the bar 83 will be uniform in both directions during the 55 portion of its cycle while it is in motion.

Thus, it will be seen that if the terminals 95 and 96 be connected to complete an electrical circuit, there will pass in that circuit a series of 60 cyclical impulses; and the duration of the interval of current flow will bear to that of the complete cycle a ratio proportional to the magnitude of the measured fluid pressure or condition represented thereby.

65 In order that the complete cycles be defined, the relative dimensions of the sector 88 and the cam 91 are so proportioned that with the pointer 85 and the associated sector 88 at the upper limit of the scale, there will still take place a momentary interruption of the circuit as the cam member 91 passes its highest point; while, with the sector in a position corresponding to the lower limit of the scale, a momentary contact will be made as the cam member passes its lowest point.

70 The particular manner of interconnecting the

receiving unit of the system with its associated transmitting unit is shown in Fig. 8. As indicated, the constant speed motors 97 and 35, of the transmitting and receiving units respectively, are supplied with electric current from suitable 5 sources 100 and 101, not necessarily in synchronism with each other, but the speeds of the motors and the ratios of associated gear trains being so selected that the time which would be required for the pointer 60 to make a complete 10 transit of the scale 61 in the receiving unit, with the braking element 27 maintained in one position, is substantially equal to the time of one complete revolution of the cam member 91 in the transmitting unit. 15

The interconnecting or transmission line may consist of a two-wire circuit 102 including the electromagnet 52 of the receiving unit, the terminals 95 and 96 of the transmitting unit and a suitable source of current, as a battery 103, all 20 connected in series, so that when the circuit is closed between the terminals 95 and 96 by engagement of the contact member 94 with the sector 88, the magnet 52 will be energized with current from the battery 103. 25

Operation

As has already been set forth, the transmitting unit of the system, connected into an electrical circuit, becomes a source of cyclical impulses 30 in each of which the duration of current flow will bear to that of the complete cycle a ratio proportional to the magnitude of the measured condition. It has also been set forth that the pointer 60 in the receiving unit will take up a position 35 wherein the magnitude of its deflection across the scale will be proportional to the length of the interval in each cycle of operation during which the magnet 52 is energized. It will, therefore, be apparent that with an electrical interconnecting 40 circuit made up as hereinbefore set forth the pointer or indicator 60 on the receiving unit will tend to take up a position on the scale 61 which will be representative of, and proportional to, the magnitude of the condition measured by the 45 transmitting unit.

It will be further apparent that, while the device has been shown as embodying an electrical circuit for carrying controlled impulses of electric current as a means of transmission of the 50 magnitudes of a measured quantity I do not wish to be restricted thereto as the transmission may be otherwise accomplished; and it will be also understood by those versed in the art that the receiver mechanism herein may readily be adapted for purposes other than recording without departing from the spirit of the invention. 55

I claim:

1. In a telemetering system: a receiving device subject to transmitted electrical impulses and 60 comprising an epicyclic gear train including a normally rotating portion and a normally stationary portion, a second epicyclic gear train including a normally rotating portion and a normally stationary portion, means to impart continuous rotation to both trains, means to stop the normally rotating portion of the first-named train during transmission of an electrical impulse and permit concurrently therewith rotation of the normally rotating portion of the second-named 65 train, and vice versa, and means associated with the respective normally stationary portions of both trains for engagement therewith and subject to deflection thereby in opposite senses.
2. An electrical impulse-responsive device 70

adapted to reproduce proportionately the effects of electrical impulses of determined duration, said device comprising two epicyclic gear trains, each including a spindle member and a driving member, a planetary member, an impelling member, and a free-running member, all carried by said spindle member for rotation thereon, an indicating element, means whereby said indicating element may be positioned alternatively by the respective impelling members of the said trains, means to rotate continuously the driving members of said trains, and means associated with the free-running members and subject to a received electrical impulse to stop rotation of one or the other of said free-running members.

3. An electrical impulse-responsive device adapted to reproduce proportionately the effects of electrical impulses of determined duration, said device comprising two epicyclic gear trains, each including a spindle member and a driving member, a planetary member, an impelling member, and a free-running member, all carried by said spindle member for rotation thereon, an indicating element, means whereby said indicating element may be positioned alternatively by the respective impelling members of the said trains, means to rotate continuously the driving members of said trains, and electromagnetically operated braking means subject to a received electrical impulse to stop rotation of one or the other of said free-running members.

4. An electrical impulse-responsive device adapted to reproduce proportionately the effects of electrical impulses of determined duration, said device comprising two epicyclic gear trains, each including a spindle member and a driving member, a planetary member, an impelling member, and a free-running member, all carried by said spindle member for rotation thereon, an indicating element, means whereby said indicating element may be positioned alternatively by the respective impelling members of the said trains, means to rotate continuously the driving members of said trains, means associated with the free-running members and subject to a received

electrical impulse to stop rotation of one or the other of said free-running members, and means to restore an impelling element to a predetermined position when rotation of the associated free-running member is no longer stopped.

5. An electrical impulse-responsive device adapted to reproduce proportionately the effects of electrical impulses of determined duration, said device comprising two epicyclic gear trains, each including a spindle member and a driving member, a planetary member, an impelling member, and a free-running member, all carried by said spindle member for rotation thereon, an indicating element, means whereby said indicating element may be positioned alternatively by the respective impelling members of the said trains, means to rotate continuously the driving members of said trains, means associated with the free-running members and subject to a received electrical impulse to stop rotation of one or the other of said free-running members, means to restore an impelling element to a predetermined position when rotation of the associated free-running member is no longer stopped, and means to adjust the angular positions of the respective impelling elements when the latter are in a state of repose.

6. An electrical impulse responsive device adapted to reproduce proportionately the effects of electrical impulses of determined duration, said device comprising two epicyclic gear trains, means mechanically interconnecting the gear trains, a driving means common to said gear trains with the drive gears of each continuously rotated therefrom in opposite directions at substantially constant speed, mechanically interconnected indicator actuating mechanisms, follow-up means for alternately driving in opposite directions the respective indicator actuating means from the corresponding gear trains, and braking means under the control of telemetered impulses to engage one or the other of the gear trains to effect operation of its follow-up means.

CARLTON W. BRISTOL. 45
